INVENTOR,
H. R. ATKINSON.
By Martin P. Smith,
ATTY.

UNITED STATES PATENT OFFICE.

HARRY R. ATKINSON, OF LOS ANGELES, CALIFORNIA.

MOTOR-VEHICLE-HEADLIGHT INDICATOR.

Application filed August 21, 1924. Serial No. 733,293.

To all whom it may concern:

Be it known that I, HARRY R. ATKINSON, a citizen of the United States, residing at Los Angeles, in the county of Los Angeles and State of California, have invented certain new and useful Improvements in Motor-Vehicle-Headlight Indicators, of which the following is a specification.

My invention relates generally to head-lights for motor vehicles and more particularly to an indicating or tell-tale device that is adapted to be associated with a head-light for the purpose of producing, while the headlight is lighted and functioning properly, a visible signal that may be readily observed by the driver of the vehicle with which the device is associated.

Further objects of my invention are, to provide an indicating or signalling device of the character referred to that is relatively simple in structure, capable of being associated with practically all forms of motor vehicle headlights, entirely automatic in its signalling functions, very compact and presenting a neat and finished appearance when properly positioned upon the housing of a headlight.

With the foregoing and other objects in view, my invention consists in certain novel features of construction and arrangement of parts that will be hereinafter more fully described and claimed and illustrated in the accompanying drawings in which:

Fig. 1 is a perspective view of a headlight housing with an indicating or signalling device of my improved construction in position for use thereupon.

Fig. 2 is an enlarged vertical section of Fig. 1.

Referring by numerals to the accompanying drawing which illustrates a practical embodiment of my invention, 10 designates the housing of a headlight such as is ordinarily used on motor vehicles, 11 the bracket 45 that supports said housing, 12 the reflector within the housing, 13 the electric lamp and 14 the lens, all of said parts being of ordinary construction, and well known in the art.

In order to accommodate my indicating or tell-tale device, small apertures 15, in vertical alignment with each other and with lamp 13, are formed in the upper portions of housing 10 and reflector 12.

Secured in any suitable manner to the top of housing 10 is the base 16 of a small hous-

ing 17, preferably of metal, said base having an aperture 18 that coincides with the aperture 15 in housing 10.

Formed in the rear wall of this small housing 17 is an opening 19 and arranged thereover and suitably secured to said housing is a disc 20, of transparent material, preferably glass, and either clear or colored.

I prefer to use in the rear wall of this housing 17 a small colored glass disc having facets on either one or both of its faces, inasmuch as said provision tends to throw a number of concentrated light rays rearwardly from the tell-tale device.

Adjustably arranged within the housing 17 and supported by one or more adjusting screws, such as 21, that are seated in the wall of said housing, is a frame 22 that carries a small mirror 23 or member having a reflecting surface. In some instances it may be found desirable to utilize a prism as the light reflecting or refracting member or satisfactory results may be attained by coating the interior of housing 17 with light reflecting material, such as white paint or enamel, aluminum paint, or the interior of said housing may be nickel or silver plated. This reflecting member is adjusted by proper manipulation of the screws 21, so that it occupies an angular position of approximately 45° relative to vertical and horizontal planes, directly above aligned apertures 15 and 18 and to the rear of the transparent member.

Thus, whenever lamp 13 is lighted and as long as it remains lighted a small column or pencil of light will pass upward through aligned apertures 15 and by the inclined mirror 23, the light rays in the column or pencil will be projected rearwardly through member 20, toward the driver's seat in the vehicle, thus providing a readily observed signal for assuring the driver that the headlight is lighted and functioning properly.

Obviously, when lamp 13 burns out, or the circuit thereto is opened by switch or otherwise, there will be no light rays projected from the device.

Thus it will be seen that I have provided a relatively simple, practical and inexpensive device that may be readily applied to a motor vehicle headlight and which device will serve to indicate, at all times, the lighted or unlighted condition of the lamp within the headlight.

It will be understood that minor changes

in the size, form and construction of the various parts of my improved headlight indicator may be made and substituted for those herein described without departing from the spirit of the invention, the scope of which is set forth in the appended claims.

I claim as my invention:

1. The combination with a headlight housing and the reflector therein, which 10 housing and reflector are provided with apertures that are in alignment with the lamp that is associated with said headlight, of a small housing mounted on the headlight housing directly over the opening therein, 15 said small housing having an opening in its base portion that coincides with the opening in the headlight housing, a reflector adjustably arranged within said small housing, and a transparent member arranged in

the rear wall of the small housing in front 20 of said adjustable reflector.

2. The combination with a headlight housing and the reflector therein, which housing and reflector are provided with apertures that are in alignment with the lamp that is associated with said headlight, of a small housing mounted on the headlight housing directly over the opening therein, said small housing having an opening in its base portion that coincides with the opening in the 30 headlight housing, a reflector adjustably arranged within said small housing, the rear wall of the small housing in front of said adjustable reflector being provided with an opening and a faceted transparent member 35 arranged in said opening.

In testimony whereof I affix my signature.
HARRY R. ATKINSON.
